UNITED STATES PATENT OFFICE

2,424,024

MANUALLY OPERATED LEVER FOR BENDING
AND SHEARING METAL RODS

Jesse Garton, Hawthorn, Victoria, Australia

Application October 4, 1945, Serial No. 620,242
In Australia October 26, 1944

2 Claims. (Cl. 153—2)

1

This invention relates to a combination hand appliance or tool for bending and also for shearing light metal rods, bars and the like.

The object of the invention is to provide a compact and simply constructed appliance or tool which will efficiently perform either of the two operations mentioned and is convenient and easy to operate by hand.

The appliance consists basically of a slotted holder in which the rod or bar to be operated on is placed, a lever movable about said holder, a bending pin or abutment carried by the lever and adapted, when the lever is moved in one direction, to act on the rod or bar to bend same, and a shearing member also carried by the lever and movable in sliding relationship to the surface of the slotted holder to shear the rod or bar when the lever is moved in the opposite direction.

The slotted holder is rigidly secured to a base plate and the lever is arranged to pivot on the holder and is actuated preferably through a hand-lever and link connection to secure the requisite leverage.

The appliance is more fully described aided by reference to the accompanying drawings wherein:

Fig. 1 is a perspective view of the complete appliance.

Fig. 2 is a vertical section taken substantially on the line 2—2 of Fig. 1.

Figs. 3 and 4 are side views illustrating the use of the appliance for bending metal rods or bars.

Fig. 5 and 6 are similar views to Figs. 3 and 4 but illustrating the use of the appliance for shearing the rods or bars.

As is shown in these views, the appliance comprises a base plate 1 on which is rigidly supported the slotted holder 2. Said holder has a cylindrical head portion 3 and a shank portion 4 of reduced diameter which is secured in a hole 5 in the base plate. The head has a diametrical slot 6 in which the metal rod or bar to be bent or sheared is placed.

A bar or strap as 7 is secured to the rear of the base plate 1 as by welding and carries a screw 8 which is screwed into a tapped hole 9 in the holder 2 to secure it to the base plate.

The portion 10 of the holder between the shank part 4 and the head 3 is of circular form and constitutes a pivot or bearing for the lever 11 so that said lever is movable about the holder.

The lever 11 carries a bending pin or abutment 12 which lies adjacent to the upper end of the slot 6.

The lever 11 also carries a shearing element or

2

blade 13 so arranged as to slide around or follow the periphery of the head 3 of the slotted holder and move across the lower end of the slot 6.

The lever 11 is actuated through a link connection 14 from a hand-lever 15 pivoted at 16 to the base plate 1. The hand-lever may be of any approved length to secure substantial leverage, and a series of adjustment holes 17 may be provided in it and the link 14 so that the leverage can be varied as required. The link 14 is detachably connected to the hand-lever 15 by means of a removable screw 18 having a suitable turning handle as 19. The screw 18 may be anchored to the hand-lever 15 by means of a chain 20 or the like, see Fig. 1, to prevent loss or misplacement.

In the use of the appliance, the rod or bar 21 to be operated on is held in the slot 6 of the holder. If it is desired to bend the rod or bar, it is held in desired position in relation to the bending pin 12 as shown in Fig. 3 and the lever 11 actuated by the hand-lever 15 in the direction of the arrow in Fig. 3 to move said pin against the rod or bar and bend same away from the head 3 as shown in Fig. 4 to the extent required.

For shearing, the rod or bar 21 is held in correct position in relation to the lower or shearing end of the slot 6 in the holder as shown in Fig. 5 and the lever 11 actuated now in the reverse direction to cause the shearing element or blade 13 to move across the lower end of the slot and shear the protruding portion 22 of the rod or bar as shown in Fig. 6.

Preferably during the bending operation, the link 14 is connected to the hand-lever 15 by utilizing the two outermost of the holes 17 of said hand-lever and link while, for the shearing action, the two innermost of said holes 17 are used giving greater leverage when shearing the rod or bar.

The slotted holder 2 is rigidly secured to the base plate 1 to prevent rotation by any suitable means, such as for instance, by inserting one or more small screws or keys between the shank part 4 and the hole 5.

The base plate 1 preferably has side lugs or flanges 23 by which it can be secured to a suitable support either horizontal or vertical. Said lugs or flanges may, for convenience of manufacture, be welded as at 24 to the base plate.

The bending pin 12 may, if desired, be provided with an anti-friction roller as 25 as shown in Figs. 1 and 2 to facilitate bending of the rod or bar.

The appliance can be secured to a post, col-

umn or the like in a vertical position as shown or secured to a suitable flat surface such as a work bench or the like. It can also be secured in a vise or the like by clamping the jaws of the vise onto the rear strap or band 7 of the appliance.

The appliance, although simple, forms an efficient and extremely useful tool suitable for use by engineers, farmers, builders and others who, in their business, require to bend and/or shear light metal rods or bars.

What I claim is:

1. A combination hand appliance for bending and shearing metal rods or bars comprising a base plate, a holder carried thereby and having a cylindrical head provided with a slot in which the rod or bar to be operated on is placed, a lever movable about said holder, a bending pin or abutment carried by the lever and adapted, when the lever is moved in one direction, to move across one end of the slot in the holder and act on the rod or bar to bend it, and a shearing member also carried by the lever and movable in sliding relationship with the periphery of the head of the holder to move across the other end of the slot and shear the rod or bar when the lever is moved in the opposite direction.

2. A combination hand appliance for bending and shearing metal rods or bars comprising a base plate, a holder carried thereby and having a cylindrical head provided with a diametrical slot in which the rod or bar to be operated on is placed, a lever movable about said holder, a bending pin or abutment carried by the lever and

adapted, when the lever is moved in one direction, to move across one end of the slot in the holder and act on the rod or bar to bend it, a shearing member also carried by the lever and movable in sliding relationship with the periphery of the head of the holder to move across the other end of the slot and shear the rod or bar when the lever is moved in the opposite direction; a hand-lever pivoted to the base plate and a link connecting said hand-lever to the first mentioned lever so that the latter is actuated by the hand-lever, the connection of the link to the hand-lever being adjustable to provide different leverages for the bending and shearing operations.
